UNITED STATES PATENT OFFICE

1,943,491

GEAR-WHEEL PUMP FOR ARTIFICIAL SILK SPINNING MACHINES

Fritz Sieper, Barmen-Langerfeld, Germany, assignor to the firm Barmer Maschinenfabrik A.-G., Barmen-Rittershausen, Germany

Application October 14, 1929, Serial No. 399,644,
and in Germany October 25, 1928

2 Claims. (Cl. 103—126)

The housings or casings of gear-wheel pumps for artificial silk spinning machines have hitherto been adapted as regards their shape to the various methods of securing them in place. The pump 5 housings therefore had to be manufactured in various shapes which gave rise to the disadvantage that the parts of the pumps could not be produced by mass-production methods.

The object of the invention is a gear-wheel 10 pump, for artificial silk spinning machines, which consists of the pump proper with its housing and of a special part or member adapted for use in the securing operations.

According to the invention therefore the essential 15 parts of the gear-wheel pump are detachably connected to a special securing or fixing member. By means of this construction a standard design may be employed for the essential parts of the pump, which may be suitably screwed to the fixing member best adapted to the requirements of 20 the case under consideration. A further advantage resides in the fact that the individual components of the pump proper can be manufactured in a simple and accurate manner, so that high 25 grade material which is difficultly workable, such as acid- and rust-proof steel, may be employed with advantage.

The accompanying drawing illustrates two constructions according to the invention by way of 30 example.

Fig. 1 is a side elevation of a gear-wheel pump having the fixing point at the top.

Fig. 2 is a front elevation thereof.

Fig. 3 is a side elevation of a pump having the 35 fixing point disposed transversely of the driving shaft and

Fig. 4 is a front elevation thereof.

The pump housing *a* which consists of front, middle and rear plates is screwed or bolted to the 40 fixing member *b* which is adapted to the desired method of fixing in each case and is formed with the fixing point or place *c*. The essential parts of the pump, which are enclosed by the housing *a* can be the same for all the various methods of 45 fixing, and be connected with the special part or member *b* according to the method of fixing adopted.

In accordance with my invention, the pump housing *a*, constructed as described, is made of 50 an acid proof material, such as acid proof steel, of which the pump gears enclosed therein are also made, so that these important and more expensive parts of the pump are designed to resist corrosion and to be thereby maintained in prime 55 working condition for a long period, thus pre-

venting imperfect action of the pump gears and leakage and ensuring at all times the supply of a correct amount of solution to the spinnerettes. The body or stock portion *b* of the pump, however, which contains the supply and discharge ducts 60 *c, d*, is made of cast iron or some other suitable lower grade material which can be readily machined or otherwise worked. This body or stock portion is also provided with an integral attaching portion or bracket *e*, so that those portions 65 of the pump which are of less importance, and which will stand corrosion without affecting the working action of the pump, are made of a material of a less expensive character and more easily worked, such as cast iron, whereby the 70 cost of manufacture and maintenance of the pump may be kept within reasonable and safe limits. My invention thus provides a pump structure of the character and for the purpose described which is more durable and much more reliable and uniformly precise in its delivery actions than pumps 75 of ordinary construction, and which, while capable of being supplied at a comparatively low cost, will in the end involve less cost than ordinary pumps because of its greater durability. 80

Having now particularly described and ascertained the nature of my said invention and in what manner the same is to be performed, I declare that what I claim is:—

1. The combination with a main supporting 85 member having a shaft bearing and having a plane face, said member having a journal bore extending perpendicularly from said plane face and opening through the back of the member and having an inlet port and an outlet port opening through the plane face; of a unitary pump 90 adapted to be secured to and removed from the plane face of said member as a unit and including three plates of equal length and width, each of said plates being provided with aligned bolt 95 holes, one of said plates being adapted to rest against said plane face and having a shaft hole and inlet and outlet ports extending therethrough and registering with the corresponding 100 openings in the main member, the second of said plates having an opening therein to receive a pump impeller and having the ports and shaft hole of the first plate opening thereinto, the third of said plates covering the second and being imperforate except for the bolt holes, a shaft 105 extending through the bore of the main member and shaft hole of the first plate and provided with an impeller located in the opening of the second plate, and bolts passing through the bolt holes 110 and screwed into the main member.

2. The combination with a main supporting member having a shaft bearing, and having a plane face, said member having a journal bore extending perpendicularly from said plane face 5 and opening through the back of the member and having an inlet port and an outlet port opening through the plane face; of a unitary pump adapted to be secured to and removed from the plane face of said member as a unit and including three 10 plates of equal length and width, each of said plates being provided with aligned bolt holes, one of said plates being adapted to rest against said plane face and having a shaft hole and inlet and outlet ports extending therethrough and register- 15 tering with the corresponding openings in the

main member, the second of said plates having an opening therein to receive a pump impeller and having the ports and shaft hole of the first plate opening thereinto, the third of said plates covering the second and being imperforate except for the bolt holes, a shaft extending through the bore of the main member and shaft hole of the first plate and provided with an impeller located in the opening of the second plate, and bolts passing through the bolt holes and screwed into the main member, all of said plates having their front and back faces plane surfaces and being of uniform thickness.

FRITZ SIEPER.
